UNITED STATES PATENT OFFICE.

ELIJAH MCCOY, OF DETROIT, MICHIGAN, ASSIGNOR TO EDWIN C. NAGEL, OF DETROIT, MICHIGAN.

LUBRICATOR.

Application filed December 18, 1922. Serial No. 607,655.

To all whom it may concern:

Be it known that I, ELIJAH MCCOY, a citizen of the United States of America, residing at Detroit, in the county of Wayne and State of Michigan, have invented certain new and useful Improvements in Lubricators, of which the following is a specification, reference being had therein to the accompanying drawings.

10 The invention relates to lubricators of that type designed for the feeding of graphite or other flaked or powdered lubricant into the lubricating fluid, and the invention consists in certain novel features of 15 construction as hereinafter set forth.

In the drawings:

Figure 1 is a sectional elevation of the lubricator;

20 Figure 2 is a horizontal section on line 2—2 of Figure 1;

Figure 3 is a view similar to Fig. 1 showing a modification.

As shown, A is the casing or container for the lubricant which is provided at its lower 25 end with the threaded nipple B for attachment to the fitting C leading to the part to be lubricated. The device is particularly designed for use on locomotives where the pulsating pressure of steam is utilized for 30 agitating and feeding the flaked or powdered lubricant. Thus, as shown, D is the conduit through which the fluid lubricant is fed to the fitting C and through the latter into the engine steam chest E. The pulsating 35 pressure of steam in the chest E will thus pass backward through the fitting C and nipple B into the container A and upon falling of the pressure, the reverse current will carry with it the flaked or powdered lubricant.

40 To insure the constant feeding of this flaked or powdered lubricant, I have devised the following construction: F is a hollow stem having its lower end engaging a threaded recess in the nipple B and its upper end preferably extending to the top of the casing A and into the hollow cap G for closing said casing. The stem F has formed in its lower portion a valve seat H which, 45 when engaged by a valve I, will cut off communication from the cup to the fitting C. When, however, the back pressure is sufficient, the valve I will be lifted from its seat 50 to permit the passage of steam into the

casing A. The passage of this steam is 55 through an annular series of ports J formed in the hollow member F. These are so arranged that when the valve I is lifted from its seat, the steam will be deflected in all directions through the ports J and into the 60 flaked or powdered lubricant, agitating the same and permitting a small quantity to be fed in the reverse direction when the current of steam is reversed. As shown in Figure 1, the valve I is in the form of a ball 65 valve and stem F is provided with an upper seat K above the ports J cutting off communication with the chamber L in the upper portion of the stem. Ports M at the upper end of the stem establish communication between the chamber L in the casing A and 70 serve to equalize the pressure above and below the valve H. However, in operation, the valve I, when lifted from its lower to its upper seat, will cause the momentary injection of steam through the ports K into the mass of flaked or powdered lubricant and when the pressures have equalized, a small portion of the lubricant will be carried 75 downward and will pass into the fitting C before the valve I again engages its lower seat.

With the construction shown in Figure 3, in place of the ball valve I, a cylindrical valve I' is used and an adjustable stop O 85 formed by a threaded stem serves to limit the amount of movement of the valve.

One of the advantages of the construction, as shown in Figure 1, is that the hollow stem F is accessible from the top of the 90 cup and in case of any clogging can be readily removed and replaced. A slot P at the upper end of the stem serves for its engagement with a screw driver by which the stem may be easily unscrewed.

95 What I claim as my invention is:

1. In a lubricator for the feeding of flaked or powdered lubricant, the combination with a casing, of a hollow stem extending longitudinally thereof and provided with ports at its upper end communicating with the casing, said stem also having a series of three or more inclined ports between the hollow interior thereof and the lower portion of the casing, said ports being arranged to lead upwardly in all directions to deflect the steam in all directions and agitate the flaked or powdered lubricant in 100 105

said chamber, and a normally closed automatic valve in said hollow stem adapted to be actuated by the pulsating pressure.

2. In a lubricator for the feeding of flaked or powdered lubricant, the combination with a casing, of a hollow stem extending upwardly in said casing and provided with ports communicating with the upper and lower portions of said casing, a normally closed valve in said hollow stem, and seats for said valve above and below the ports communicating with the lower end of said casing for the purpose described.

3. In a lubricator for the feeding of

flaked or powdered lubricant, the combination with a casing and a cap therefor, of a hollow stem extending upwardly within said casing with its upper end accessible when said cap is removed, an annular series of ports leading from said hollow stem to the lower portion of said casing, a second series of ports communicating with the top of said casing, a gravity closed ball valve within said hollow stem, and seats for said valve above and below said annular series of ports.

In testimony whereof I affix my signature.

ELIJAH McCOY.
